2 SHEETS—SHEET 2.

UNITED STATES PATENT OFFICE.

UTLEY WEDGE, OF ARDMORE, PENNSYLVANIA.

MANUFACTURE OF SULFURIC ACID.

1,104,590.

Specification of Letters Patent. Patented July 21, 1914.

Application filed September 18, 1909. Serial No. 518,395.

To all whom it may concern:

Be it known that I, UTLEY WEDGE, a citizen of the United States, residing in Ardmore, Pennsylvania, have invented certain 5 Improvements in the Manufacture of Sulfuric Acid, of which the following is a specification.

The object of my invention is to facilitate the manufacture of sulfuric acid, especially 10 that produced from blast furnace gases. This object I attain in the manner herein-after set forth, reference being had to the accompanying drawing, which represents, in diagrammatic form, apparatus constructed 15 for the carrying out of my invention, Figure 1 being a side elevation of the apparatus, and Fig. 2 a plan view of the same.

In the manufacture of sulfuric acid from blast furnace gases much difficulty has been 20 experienced because of the high temperature of the blast furnace gases, the large amount of steam created by moisture in the blast furnace charge, and the presence of excessive amounts of nitrogen or carbonic acid 25 gas which, in addition to acting as diluents of the sulfurous acid gas, also serve to carry into the sulfuric acid process heat units out of proportion to the sulfuric acid produced. It is desirable to utilize this heat in the 30 Glover tower for the concentration of sulfuric acid, but, when this heat is so utilized the gas leaves the Glover tower and enters the lead acid chambers either at an abnormally high temperature or carrying an excessive amount of steam. In the one case 35 the high temperature causes destructive action upon the lead walls and tops of the chambers owing to excessive chemical action at such high temperature, and in the other case, the amount of steam entering the 40 chambers is so excessive as to greatly dilute the sulfuric acid produced or interfere with the securing of proper chemical reaction, resulting in the consumption of excessive 45 amounts of nitrate of soda or nitric acid. I find that these objections can be overcome and the production of the acid facilitated if the mixture of sulfurous and nitrous 50 gases issuing from the Glover tower is caused to pass at relatively high speed through a series of chambers of small cross section and presenting a cooling surface which, in proportion to the cubic capacity of the chamber, is much greater than that 55 of the ordinary lead chamber. By reason of the rapid radiation of heat due to the

large area of exposed surface of these chambers, injurious action of the gases upon the lead, because of their high temperature, is minimized, and, especially if the passage for 60 the flow of the gases is of a tortuous character, the intimate admixture of the gases and the steam during such flow will result in the formation of the sulfuric acid more rapidly than in the ordinary chamber of large capacity, the surplus steam being absorbed or 65 incorporated in the sulfuric acid which is produced, thereby, in great measure, relieving any subsequent chamber or chambers of the series from the performance of this duty. 70

In the drawing, 1 represents the blast furnace or other generator of sulfurous gas, 2 the Glover tower into which the gases are introduced from the blast furnace and from which they pass to a manifold 3, having 75 branches leading to the primary members of a plurality of rows of lead towers 4, the gases being withdrawn from the last members of the rows by means of suitable exhaust fans 5 and driven by the latter into 80 the usual lead chambers 6 for the completion of the process. The towers 4 have very limited cross sectional area in proportion to their height, being about 10 feet square and 70 feet high, and they are composed of 85 aprons of lead supported by any suitable external framework, the towers being connected alternately at top and bottom, as shown in Fig. 1, so that the gases and steam in passing through the towers are caused to 90 follow a tortuous course and are subjected to constant agitation and admixture during their flow. Any desired number of these towers may be employed according to the capacity of the apparatus. In one apparatus 95 which I have constructed, where the temperature of the blast furnace gases when they leave the furnace is from 1100° F. to 1800° F. and the temperature of the gases after they leave the Glover tower is from 100 240° F. to 250° F., I have employed 72 towers, arranged in eight rows of nine towers to the row with the idea of so reducing the temperature of the gases in their passage that they will issue from the final towers at 105 a temperature of about 190° F., at which temperature they enter the ordinary lead chambers 6. The effect of using this bank of towers as compared with the use of an ordinary lead chamber will be understood 110 when it is borne in mind that a lead chamber 50 feet square and 75 feet high, while

2
having a cubic capacity of 187,500 feet presents a surface area of only 16,500 feet, or considerably less than one tenth of a square foot of surface for each cubic foot of capacity, whereas 72 towers each 10 feet square and 70 feet high, while possessing a capacity of 504,000 cubic feet, will have a surface area of 208,800 feet, or more than four tenths of a square foot of surface for each 10 cubic foot of capacity, and the same proportions hold good irrespective of the number of towers of this size which may be employed. This is due, in some measure, to the very small percentage of the total 15 surface area of each tower which rests upon the ground and is therefore unavailable as a cooling surface, although the chambers 4 may be disposed horizontally instead of vertically, if they are so supported that the 20 air can gain access to their under sides.

I do not desire to limit my invention to a tower or chamber of such size or disposition that it presents a surface area as high in proportion to cubic space as that above indicated, as good results can be obtained with 25 a chamber which is so proportioned or disposed that the surface area presented is as low as three tenths of a square foot to each cubic foot of chamber space.

30 The steam combined with the gases is condensed by the lowering of the temperature of said gases, but this condensation does not take place so rapidly as to dilute the acid product to any greater extent than in ordinary chamber practice, because of the very 35 rapid formation of sulfuric acid, thus overcoming an objection which applies to apparatus in which water cooled pipes are introduced for the purpose of quickly reducing 40 the temperature of the gases.

The towers alone may be employed, if desired, although I prefer to combine them with the large lead chambers 6 for the completion of the process, as said lead chambers 45 are sufficiently effective if the temperature of the gases supplied thereto is not abnormally high.

50 The intimate admixture of the gases and the rapidity of their flow through the lead chambers is an important feature of my invention, hence I so proportion even the large lead chambers 6, in respect to the volume of flow, that the rate of flow of the gases therethrough will exceed twelve feet per minute, 55 this being many times faster than in any previous practice with which I am familiar.

In apparatus which I have constructed, the rate of flow of the gases to each row of

lead towers 4 approximates ten thousand cubic feet per minute, the flow from four rows 60 of towers being concentrated, and passed through a plurality of large lead chambers 6, which are connected in series. These large lead chambers are each about fifty feet square and 70 feet high, presenting a cross-sectional area of twenty-five hundred square feet, and they receive about forty thousand cubic feet of gas per minute, giving a rate of flow of about sixteen feet per minute, the rate of flow through the small lead towers 4 70 being proportionately faster, or about one hundred feet per minute.

Throughout its course the sulfur content of the sulfurous gas is progressively decreasing and there is no adulteration of rich gas 75 by admixture with spent or partly spent gas, as in apparatus in which the gas is withdrawn from one chamber of a series and introduced into a preceding chamber. The gases escaping from the final chamber 6 of 80 the series are treated, as in the ordinary practice.

I claim:

1. In sulfuric acid apparatus, the combination of a sulfurous gas generator, a Glover 85 tower which receives said gas, and a plurality of lead chambers receiving the discharge from said Glover tower, said lead chambers being disposed as vertical towers and connected in series alternately at top 90 and bottom and presenting a surface area equaling or exceeding three-tenths of a square foot for each cubic foot of chamber space.

2. In sulfuric acid apparatus, the combination of a sulfurous gas generator, a Glover tower receiving the gas therefrom, a plurality of lead chambers disposed as vertical towers and receiving the discharge from said Glover tower, said lead chambers being connected in series alternately at top and bottom and presenting a surface area equaling or exceeding three-tenths of a square foot for each cubic foot of chamber space, and lead chambers into which the last of said 105 vertical towers discharges, said latter lead chambers each presenting a much less area of surface for each cubic foot of capacity than said towers.

In testimony whereof, I have signed my 110 name to this specification, in the presence of two subscribing witnesses.

UTLEY WEDGE.
